VACUUM TUBE ELECTRODE

Everett P. Loppacker, Bloomfield, N. J.

Application November 14, 1934, Serial No. 752,929

2 Claims. (Cl. 250—27.5)

This invention relates to an improved electrode for vacuum tubes used in radio and related arts.

A primary object of the invention is to provide an electrode element formed from a single piece 5 of homogeneous material entirely free from any joints whatever.

In accomplishing this object the electrode is first stamped into cup shape from a flat sheet, and the parts of the cup are then appropriately 10 formed to yield the structure desired for the particular tube.

Another object is to reinforce the open end of the electrode by strengthening means, such as a flange or bead, to increase its resistance to 15 distortion.

Among other objects of the invention are the production of an electrode having increased wall area, and having great strength and rigidity, and also being relatively free from microphonic noises.

20 While preferred forms of the invention are disclosed herein for purposes of illustration, various changes may be made in the structure without departing from the spirit of the invention as hereinafter set forth and claimed.

25 In the drawing:

Fig. 1 is a side elevation of a plate element embodying the invention.

Fig. 2 is a section on line 2—2 of Fig. 1.

Fig. 3 is a fragmentary vertical section.

30 Fig. 4 is a fragmentary horizontal section.

Fig. 5 is a fragmentary plan view showing in detail the perforations.

Fig. 6 is a perspective view of a modified shape of electrode.

35 Fig. 7 is a fragmentary side elevation showing a modified top construction.

Fig. 8 is a fragmentary section showing a further modification.

Referring to the drawing more particularly, 40 the electrode element illustrated in Fig. 1 is a cup-shaped member comprising a cylindrical side wall 10 and a top 11. This cup-shaped member is originally produced by stamping or otherwise forming it from a sheet of suitable material. The

45 top 11 is then punched to give the formation desired for the particular tube, and the side wall is perforated by any preferred method, as by a rolling operation, or these walls may be formed with perforated protrusions 12, as illustrated in Figs. 3 and 4. Parts of the side wall are left imperforate, shown at 13, and are indented so that support wires may be conveniently attached to 50 these parts, as by spot welding.

55 A one-piece homogeneous element formed in the

manner described avoids the necessity for a joint connecting the top to the side wall, as well as the necessity for a vertical joint in the side wall, and has the following advantages:

1.—Accuracy of manufacture

By stamping the cup from a single sheet of metal the exact dimensions and alignment of the parts can be controlled within more narrow limits than where the electrode is assembled from several separate pieces.

2.—Strength

The one-piece electrode has greater strength and rigidity than an assembled electrode.

3.—No looseness possible

An electrode assembled from separate pieces of tin has slight looseness between parts that is present from the beginning due to defective assembly, or which develops in use due to the expansion and contraction under repeated heatings and coolings, especially where the tube is subjected to continual vibration as in an automobile radio. No such looseness can be present in the one-piece 25 electrode of this invention.

4.—Avoids distortion

Where a rolled tinner's seam is used to join separate parts, the rolling causes local stresses in the metal, and these stresses cause distortion of the electrode when it is heated in the bombardment process and in use.

5.—Avoids microphonic noises

For the reasons pointed out above the one-piece electrode is free from many of the causes of microphonic noises in tubes, these noises causing the rejection of a high percentage of tubes during manufacture as well as frequent cases of dissatisfaction in use.

In order to further stiffen the open end of the electrode it may be formed with a flange 14, and if still greater rigidity is desired a bead 15 may also be used, or either bead or flange may be used 45 alone. This reinforcing of the open end of the electrode cooperates with the one-piece construction to form a strong electrode that will hold its true cylindrical form under repeated heatings.

Where the protrusions 12 are used the inclosed 50 surface area is greater than where wire gauze or flat perforated metal is used.

Another way of increasing the surface area is shown in Fig. 8 where the perforated side wall is formed with corrugations 16, the ridges of 55

which run horizontally along the side walls of the electrode.

The advantages of increased wall area are that the tube runs cooler, gives less back emission and gives a greater area for the electronic movement.

The present invention may be applied to electrodes of various shapes, one of rectangular form being illustrated in Fig. 6, and the top may be formed to suit the requirements of the tube, a partly conical top being shown at 17 in Fig. 7.

The electrode of this invention may be used either as a "plate" or as a "grid", and due to its rigid one-piece construction, it will maintain the characteristics for which it is designed under all temperatures and conditions of use.

I claim:

1. An electrode for a vacuum tube comprising, a top, a side wall connected with the top, most

of the area of the side wall being formed with perforations, the continuity of perforations in said wall being interrupted to provide vertically extending imperforate parts of the side wall for the attachment of support wires.

2. An electrode for a vacuum tube comprising a top formed with an aperture, and a cylindrical wall having an open end and formed homogeneous with the top, the top and side wall forming a single piece free from joints, most of the area of the side wall being formed with perforations, vertically extending parts of the side wall being bent inwardly and left imperforate for the attachment of support wires, the side wall being bent into a reinforcing part extending circumferentially around the side wall adjacent the open end.

E. P. LOPPACKER.
